Howard & Howard

UNITED STATES PATENT OFFICE.

HARRY A. F. CAMPBELL, OF PHILADELPHIA, PENNSYLVANIA.

LOCOMOTIVE CYLINDER STRUCTURE.

Application filed November 18, 1927. Serial No. 234,174.

My invention relates to certain improvements in locomotive cylinder structures, of the type in which the live steam pipes are outside of the main cylinder structure.

5 Heretofore, these pipes have been separate units, the same being secured to necks on the cylinder structure and to the steam pipes in the smoke-box of the locomotive. This necessitated accurate fitting of the gaskets 10 to prevent leakage.

The object of my invention, therefore, is to make these outside steam pipes integral with the cylinder casting, obviating any joints and dispensing with packing and 15 gaskets.

In the accompanying drawing:

Fig. 1 is a transverse sectional view through the cylinder structure, boiler and frame of the locomotive on the line 1—1, 20 Fig. 2; and

Fig. 2 is a side view.

1—1 are the two side frames of the locomotive, and 2 is the boiler. 3 is the cylinder structure made in a single casting, or in two 25 castings bolted together in the usual manner. This structure rests directly on the frames 1—1 and is bolted thereto in any suitable manner.

Cast integral with the cylinder structure 30 are the cylinders 4—4 and valve-chests 5—5 of the usual type. The valve-chests communicate in the ordinary manner through passages with both ends of the cylinders 4—4, and the exhaust passages 6—6 communicate with the valve-chests 5—5, passing through trunks 7 extending from the valve-chests to the centre of the structure. These 35 exhaust passages 6—6 communicate at their outer ends 6^a with any suitable exhaust nozzles.

8 is the saddle of the cylinder structure, cast integral with the cylinders and sup-

ported not only by the trunks of the upper passages 6 but by ribs 9, as clearly shown in Fig. 2. On this saddle rests the boiler 2. 45

Cast integral with the cylinder structure and extending from the valve-chests 5 to the saddle 8 are the live steam pipes 10. These pipes not only materially strengthen the saddle at its outer ends but also provide 50 a jointless communication between the steam supply pipes 11 in the smoke-box 12 of the boiler and the live steam spaces of the valve-chests. This construction also obviates the cutting of additional holes in the shell of 55 the smoke-box.

By this arrangement the saddle can be readily mounted on the frames, and the boiler can be mounted on the saddle, which is complete in itself, including both the inside exhaust passages and the outside steam 60 passages, these passages being open on all sides, thus allowing for inspection, or repairs in case of leakage, and can be readily enclosed within suitable lagging, if found 65 necessary.

I claim:

1. A locomotive cylinder structure, having valve-chests; a saddle on which a boiler is located; internal exhaust passages; and outside steam pipes extending from the saddle 70 to the valve-chest and made integral therewith.

2. A locomotive cylinder structure made in a single casting and consisting of a centre 75 portion located on the frame of the locomotive and having therein exhaust passages; two cylinders; valve-chests above the cylinders communicating with said cylinders; a saddle on which a boiler is located; and outside steam pipes extending from the saddle 80 to the valve-chests and made integral with both the valve-chests and the saddle.

HARRY A. F. CAMPBELL.
